PAGE 2

Fig. 4

FIG. 1 is a front elevational view of a data receiving and transmitting console showing our new design.

FIG. 2 is a side view of same.

FIG. 3 is a top view of same.

FIG. 4 is a front three-quarter perspective view of same.

FIG. 5 is a rear three-quarter perspective view of same.

The essential features of our design reside in the portions shown in solid lines.

We claim:

The ornamental design for a data receiving and transmitting console as shown and described.
